[57] ABSTRACT

[21] Appl. No.: 497,980

This invention consists of a terminal for use in the marine transportation of cargo from, to or through regions in which surface transportation is undesirable. The apparatus in which the cargo is transported is a submarine cargo vessel. This submarine cargo vessel is loaded and unloaded at an underwater terminal comprising a structure functioning much as an underwater hangar such that the submarine cargo vessel may "surface" underwater where it may be loaded or unloaded and where certain work may be performed on the vessel.

FIG. 2

SUBMARINE CARGO TERMINAL

BACKGROUND OF THE INVENTION

A. Field of the Invention

This invention pertains to the submarine transportation of cargoes between points where the condition of the ocean makes surface transportation impossible or undesirable and more specifically to an underwater terminal where the vessel may be loaded or unloaded and serviced.

B. Description of the Prior Art

The prior art contains many references to the use of submarines for the transportation of cargo. Examples are found in U.S. Pat. Nos. 2,989,937; 3,085,533; 3,648,635; 3,704,678; 3,080,583.

It is also known to have submarines adapted for traveling under ice. Such is shown for example in U.S. Pat. No. 1,868,948.

Many different types of underwater or floating storage tanks and terminals are also known in the prior art. Examples of these are in U.S. Pat. Nos. 2,655,888; 3,299,645; 3,548,516; 3,552,132; 3,646,771, and 3,698,197.

SUMMARY OF THE INVENTION

My invention is a terminal for use in the transportation of cargo by water between a producing point and a consuming point, and is particularly adapted for use where surface conditions at either one or both ends of the voyage, or enroute, render surface transportation impossible or undesirable.

My terminal comprises a special structure which allows the submarine bulk cargo vessel to "surface" under water. This structure contains an air space pressurized to the same extent as the waters surrounding the structure, thereby excluding water and providing a free surface within the structure with a hyperbaric air space above it. After surfacing into this hyperbaric air space the submarine cargo vessel may be loaded or unloaded. Alternatively, the vessel may be of the type described in another U.S. Patent application assigned to the same assignee, and may use my terminal for dropping of a loaded cargo section and picking up an empty one, or vice versa. Means are also provided inside this structure for transfer of crew, provisions, stores, etc. If desired, work may be performed in the hyperbaric atmosphere on the accessible parts of the submarine cargo vessel.

While the prior art, as pointed out above, does show various types of underwater terminals, none shows a submarine terminal containing a hyperbaric air space into which a submarine vessel may surface.

BRIEF DESCRIPTION OF THE DRAWINGS

FIG. 1 is a transverse section of the submarine terminal according to the invention.

FIG. 2 is a longitudinal section of the submarine terminal taken along the line 2--2 of FIG. 1.

DESCRIPTION OF THE PREFERRED EMBODIMENT

A terminal arrangement according to my invention may be seen in FIGS. 1 and 2. In this embodiment the terminal is located in the Arctic where a layer of ice 1 covers the ocean and renders surface transportation impractical. What may be termed a submarine hanger 2 is built offshore in water of such depth as to remove

the structure from surface influences such as storms or ice and yet provide enough depth for maneuverability of submarine cargo vessels.

The hanger 2 is in effect an inverted box and may for example be anchored to the sea floor 3 by means of the legs 4. The box is comprised on one side by the roof 5 and on four sides by the walls 6. These five sides enclose a space 7 which is at the same pressure as the surrounding sea water such that water is excluded from the inside of the structure thereby forming a hyperbaric space — that is, a space in which the pressure is higher than atmospheric pressure — above the free surface 8. The space may have any gas or gases in it, such as air. The side walls extend below the free surface 8 several feet to contain leaks or spills which may occur in the hanger 2.

Extending approximately down the middle of the hanger 2 is a pier 9 which has provisions for docking submarine cargo vessels 10. Mounted on the pier 9 is a control space 11 which is at atmospheric pressure. It may be equipped with an air lock (not shown) for entry into the hyperbaric space 7. Living quarters and other amenities may be provided in the control space 11 for the terminal crew.

Extending from the control space 11 is a transfer trunk 12 which serves for transferring personnel, stores, etc. from the submarine cargo vessel 10 into the control space 11. The control space 11 in turn is connected to an elevator and service shaft 17 which connects with a tunnel 13 which may for example extend to shore (not shown).

Also on the pier 9 are facilities 14 for loading or unloading the submarine cargo vessel. These may be for example in the form of a loading arm 14 which connects with a cargo riser 15 shown particularly in FIG. 2. The cargo riser 15 connects with the cargo transport means 16 which parallels the tunnel 13 running to shore. This embodiment is particularly adapted for fluid bulk cargo but other arrangements are contemplated for other types of cargo. The transfer trunk may be used to load and unload passengers from the vessel 10.

The submarine cargo vessel 10 shown in FIGS. 1 and 2 is of a form described and claimed in another U.S. Patent application assigned to the same assignee. It comprises a propulsion module 20 and a cargo section 21 detachable from the propulsion module. The hanger 2 may be used for loading or unloading this submarine cargo vessel 10, as is described above, or it may be used if any type of routine or emergency repair work is necessary on the submarine cargo vessel. The advantages of being able to do such work in the hyperbaric space 7 rather than under water are tremendous as is well known in this art.

As a further alternative, the propulsion module 20 could detach from the cargo section 21 and then pick up another cargo section in the hanger 2 — the one at the left in FIG. 1 for example, which could have been moored in the hanger serving as a storage tank as described in the patent application noted above.

While the drawings show a hanger 2 adapted to dock two submarine cargo vessels at one time, the structure need not be thus limited. It could be designed to hold any number of such vessels. In any case, however, it would probably be desirable (but not necessary) to isolate the bays from one another for safety. A leak at an isolated location then would not jeopardize all the bays.

My underwater terminal could be used at both ends of a trade route, for example the route bringing crude oil from Prudhoe Bay, Alaska, to the East Coast of the United States. Whereas ice is no problem off the East Coast, it may be desirable that the terminal be free of all weather influences. It would also be totally out of sight, which is a highly desirable feature for industrial facilities in this day and age. More importantly, it would present no obstruction at all to surface ship traffic which would serve greatly to reduce the hazard of oil spills.

What I claim is:

1. A terminal for submarine vessels comprising:

a structure fixed entirely beneath the surface of a body of water;
 said structure containing a space empty of water open on at least one side to the body of water;
 the pressure in said space being at the same pressure as the surrounding water such that said water is excluded from said space;
 pier means on the surface of the water in said space;
 means for loading and unloading cargo from said submarine vessel in said space;
 and means giving humans access to the exterior of said submarine vessels in said space.
